SEPARATING WAX FROM OIL

Harold V. Atwell, Hammond, Ind., assignor to
Standard Oil Company, Chicago, Ill., a corpora-
tion of Indiana

Application October 26, 1931, Serial No. 571,150

4 Claims. (Cl. 196—19)

This invention relates to a process for separating wax from oils and it pertains more particularly to the dewaxing of viscous petroleum lubricating oils to obtain the desired low pour point characteristics.

In the manufacture of petroleum lubricating oils it is necessary to remove substantially all of the wax in order that the oil may flow freely at low temperatures. This is usually accomplished

10 by diluting a viscous wax-bearing oil with a light diluent, such as naphtha, chilling the mixture to about —20 to —40° F. to separate out the wax, and mechanically separating the wax from the diluted oil. In order to obtain an oil of the very 15 lowest pour test consistent with its viscosity, it may even be necessary to chill to —60° F. The ease with which the wax may be separated from the oil depends on the form in which the wax crystallizes, the solubility of the wax in the diluted oil, the viscosity and specific gravity of the diluted oil, etc. under the temperature and pressure conditions of the dewaxing apparatus. The object of my invention is to provide a diluent which 20 will give oil mixtures of extremely low viscosity and low specific gravity, which will dissolve substantially no wax and which will bring about the crystallization of the wax in such a manner that it can be easily separated from the diluted oil. A further object is to provide a system for 25 refrigerating the oil conveniently and economically and in such a manner that the crystallized wax will be readily filterable from the oil.

I have discovered that certain chlorine and fluorine derivatives of light hydrocarbons are remarkably effective as antisolvents and diluents for the separation of wax from oil. In order to obtain the low temperatures necessary I require halogenated solvents with boiling points lying below —20° C. The following chlorine and fluorine compounds are examples of such solvents which I may employ: methyl chloride, methyl fluoride, ethyl fluoride, difluoro-methane, trifluoro-methane, chloro-fluoro-methane, dichloro-difluoro-methane, monochloro-difluoro-methane, 40 and monochloro-trifluoro-methane.

These solvents are characterized by their low viscosity and low solvent power for wax in addition to their low boiling points. They can be liquefied by pressure and used as diluents for the 45 oil and wax and refrigeration can be obtained by directly vaporizing a portion of the diluent from the solution. I may, if desired, use mixtures of these diluents with light hydrocarbons, such as propane, isobutane or mixtures of propane and butane. Such mixtures have the advantage of

remaining unchanged in composition after distillation due to the similarity in boiling points of the possible components. The invention will be more clearly understood from the following detailed description of a preferred embodiment.

In the accompanying drawing, which forms a part of this specification, I have diagrammatically shown an elevational plan of my improved system.

The diluent storage tank 10 is preferably designed to withstand pressures of several hundred pounds and it may be insulated and provided with means for cooling the diluent which is stored therein. The diluent, preferably methyl chloride (B. P. —24° C.) in this example, may be mixed with a light hydrocarbon mixture of approximately the same boiling point, such as propane. In place of methyl chloride I may similarly use ethyl fluoride or dichloro-difluoro-methane or one of the other compounds previously mentioned. Higher boiling halogenated hydrocarbons are unsatisfactory because of the difficulty of attaining the low temperature necessary for refrigerating and completely dewaxing the oil.

The liquefied diluent is conducted from storage tank 10 through pipe 11 in amounts regulated by valve 12 into mixer 13, wherein it is mixed with the viscous wax-bearing lubricating oil introduced by pipe 14. The wax-bearing oil may be of any type, but in my preferred embodiment I have described a treated, wax bearing, overhead lubricating cut having a viscosity of about 1500 seconds Saybolt at 100° F.

The mixture of oil and diluent is introduced by pipe 15 into chill chamber 16 which may be a large insulated drum. Instead of introducing all of the diluent with the oil I may bypass some or all of said diluent through pipe 17, valve 18, heat exchanger 19 and pipe 20 into the base of said chamber. By this expedient I am enabled to chill the diluent in the absence of wax so that there will be no accumulations of wax in the exchanger, the chilled diluent being introduced into the body of wax-bearing oil at the base of chill chamber 16. I prefer to mix about one-third of the diluent with the oil in mixer 13, charge the chill chamber about one-third full, then discontinue the introduction of oil and introduce the remaining two-thirds of the diluent through pipe 17—20. Finally, I have about three to five parts of diluent to one part of wax-bearing oil in the chill chamber. Although the original oil-wax-diluent mixture may have had a temperature of about 100° F., the temperature of the mixture in the chill chamber, after complete dilution, may be about 40° F.

as a result of cooling the diluent in cooler 19. The temperature reduction is, preferably, gradual (3° to 5° per minute) so that it will result in the formation of relatively large wax crystals. The refrigeration is continued by withdrawing diluent vapors through conduits 21, and manifold 22, compressing them in compressor 23 and returning them through pipe 24, condenser 25 and pipe 26 to the diluent storage tank 10. In this manner I effect self refrigeration of the diluted oil-wax mixture, that is, I abstract heat from the liquid by the vaporization in situ of a portion of said liquid. The cooling from 40° to -10° F. may be at a very rapid rate, preferably about 8 to 10° F. per minute. Since the diluent itself has a tendency to throw wax out of solution, satisfactory pour points can be obtained at dewaxing temperatures of 0 to -10° F., the pour point being substantially the same as the dewaxing temperature.

The chilled slurry from chamber 16 is withdrawn by pump 27 through pipe 28 and introduced into the base 29 of filter 30 which is preferably of the vertical type wherein filter leaves 31 are suspended from a removable cover. Filtrate is withdrawn through conduit 32, valve 33 and pipe 34 to accumulation tank or sump 35, from which it may be withdrawn at desired intervals through pipe 36, exchanger 19, pipe 37, exchanger 38 and pipe 29, and introduced into boiler 40 which is heated by steam coils 41. The wax-free oil is withdrawn from the base of the boiler through pipe 42 and the diluent vapors are withdrawn through pipe 43, exchanger 38, condenser 44 and pipe 45 to diluent storage 10. Vapors from sump 35 and filter 30 are withdrawn through pipes 46 and 47 in amounts regulated by valves 48 and 49; these vapors are compressed in compressor 50 and returned through pipe 51 and condenser 52 to the storage tank 10.

When a cake has built up on the filter leaves, the slurry in the filter press is forced back into the chill chamber and the cake is removed from the leaves and withdrawn from the base of filter 30 through a large valve 54. It is then forced through conduit 55, by means of screw 56 driven by motor 57, into suitable apparatus for recovering diluent vapors and separating the wax from remaining entrained oil, without exposure to the

air where loss of valuable diluent vapors may occur.

The particular feature of my invention is the use of a wax antisolvent as a refrigerant, the refrigeration being effected by the direct vaporization thereof. This brings about a saving in the cost of refrigeration which is augmented by the fact that the refrigeration need only be carried to about -20° C. to obtain substantially complete dewaxing while heretofore it has been necessary to refrigerate with temperatures as low as -40° C. or even -50° C. The use of higher dewaxing temperatures also increases the rate of filtration and makes it possible to obtain a more complete separation of oil from wax on the filter cake.

While I have described in detail a preferred embodiment of my invention it is understood that I do not limit myself to the details hereinabove set forth except as defined by the following claims. For instance, I may use ordinary filter naphtha, benzene, or other diluents in combination with my 20 volatile antisolvents; in this case some of the antisolvent is used as a refrigerant but it exerts its influence on the physical separation of the wax in the chilling step. Other modifications will be apparent to those skilled in the art.

I claim:

1. The process of dewaxing a mineral lubricating oil comprising diluting the oil under pressure with a diluent containing monochloro-difluoromethane, cooling the diluted oil by reducing pressure and evaporating a portion of the monochloro-difluoro-methane, thus causing the wax to separate from the diluted oil, and subsequently separating the wax from the oil.

2. The method of separating wax from oil which comprises diluting a wax-bearing oil under pressure with a diluent containing a normally gaseous fluoride of a hydrocarbon containing not more than two carbon atoms, said fluoride containing less than two chlorine atoms, cooling the diluted oil to effect solidification of wax, mechanically separating the wax from the diluted oil and removing the diluent from the dewaxed diluted oil.

3. The method of claim 2 wherein the fluoride is methyl fluoride.

4. The method of claim 2 wherein the fluoride is ethyl fluoride.

HAROLD V. ATWELL.
